UNITED STATES PATENT OFFICE

150,761

DESIGN FOR A SOAP DISH

Archibald Maclay Gardner, Los Angeles, Calif.

Application March 4, 1947, Serial No. 137,346

Term of patent 3½ years

(Cl. D4—3)

To all whom it may concern:

Be it known that I, Archibald Maclay Gardner, a citizen of the United States, residing at Los Angeles, in the county of Los Angeles and State of California, have invented a new, original, and ornamental Design for a Soap Dish, of which the following is a specification, reference being had to the accompanying drawing, forming part thereof.

In the drawing:

Fig. 1 is a top perspective view of the soap dish showing my new design; and,

Fig. 2 is a bottom perspective view of the soap dish.

I claim:

The ornamental design for a soap dish, as shown.

ARCHIBALD MACLAY GARDNER.
